(57) **CLAIM**

I claim the ornamental design for a U-profile cable ways, as shown and described.

DESCRIPTION

FIG. 1 is a top view of the U-profile cable ways illustrating my new design.

FIG. 2 is a bottom view thereof.

FIG. 3 is a left hand view thereof.

FIG. 4 is a right hand view thereof.

FIG. 5 is a front view thereof.

FIG. 6 is a rear view thereof.

FIG. 7 is a perspective view from below the U-profile cable ways.

FIG. 8 is a perspective view from above the U-profile cable ways thereof.

FIG. 9 is a top view of an alternate embodiment of the U-profile cable ways illustrating my new design.

FIG. 10 is a bottom view thereof.

FIG. 11 is a left hand view thereof.

FIG. 12 is a right hand view thereof.

FIG. 13 is a front view thereof.

FIG. 14 is a rear view thereof.

FIG. 15 is a perspective view from below the U-profile cable ways; and,

FIG. 16 is a perspective view from above the U-profile cable ways thereof.

The broken lines shown in the figures are included to represent that the claimed design is of undetermined length, and form no part of the claimed design.
